(57) **CLAIM**

The ornamental design for a tub for bathing, as shown and described.

DESCRIPTION

FIG. 1 is a left, top, front perspective view of a tub for bathing embodying my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a right, top, front perspective view of a second embodiment, the top plan view being a mirror image of that shown in FIG. 2, the front elevational view being a mirror image of that shown in FIG. 3, and the rear elevational view being a mirror image of that shown in FIG. 6;

FIG. 8 is a right side elevational view thereof; and,

FIG. 9 is a left side elevational view thereof.

The broken line representation of a hole in FIGS. 1, 4, 7, and 9 is for the purpose of illustration only, and forms no part of the claimed design.
